GRIPPER MECHANISM FOR PRINTING PRESSES

Howard M. Barber, Pawcatuck, Conn., assignor to
 C. B. Cottrell & Sons Company, Westerly, R. I.,
 a corporation of Delaware

Application April 22, 1936, Serial No. 75,677

14 Claims. (Cl. 101—409)

In gripper mechanism utilizing a spring pressed tumbler cam on the end of the gripper shaft for holding the grippers in their open or closed position there is a tendency of the gripper shaft to twist, thus causing an uneven pressure of the gripper fingers upon the sheet when the grippers are closed. This is particularly true where the gripper shaft is of considerable length. This arrangement also tends to cause a hammering action of the grippers and the consequent noise and wear, due to all of the pressure being applied to the grippers at one end of the shaft whether the grippers be open or closed.

The object of my invention is to eliminate this distortion of the gripper shaft, the uneven pressure of the grippers and the noisy action of the grippers, by providing auxiliary spring means acting upon the gripper shaft at one or more points between the ends of the shaft to increase the pressure of the grippers upon their sheets when the grippers are closed, said grippers being freed from said auxiliary spring pressure when they are open. By this arrangement the tumbler spring need not be made so powerful in its action that the grippers will slap and become noisy, as is usual where the entire pressure is exerted upon the grippers by the said tumbler spring.

A practical embodiment of my invention is represented in the accompanying drawings, in which

Fig. 1 represents a plan view of a rotary sheet carrier embodying my improved gripper mechanism;

Fig. 2 represents a cross section of the same, taken in the plane of the line II—II of Fig. 1, looking in the direction of the arrows, the movable parts being shown in full lines in the positions they occupy when the grippers are closed, and in dotted lines in the positions they occupy when the grippers are open;

Fig. 3 represents a detail cross section, taken in the plane of the line III—III of Fig. 1, looking in the direction of the arrows, the movable parts being shown in the positions they occupy when the grippers are closed; and

Fig. 4 represents a similar section with the movable parts in the positions they occupy when the grippers are open.

The rotary sheet carrier 1 is herein represented as an impression cylinder of a rotary printing press, the rotary carrier shaft 2 being suitably mounted in the side frames 3 of the press.

The gripper fingers 4 are fixed on their rock

shaft 5, which shaft is located in the usual gripper recess 6 extending along the periphery of the carrier, the longitudinal walls of which recess are denoted by 7 and 8. These gripper fingers 4 are swung by the rocking of their shaft, from an open position within the recess 6 to a closed position on the pads 9 carried by the longitudinally disposed bar 10.

One end of the rock shaft 5 projects beyond the corresponding end of the rotary carrier 1 and it is there provided with a spring pressed tumbler cam 11 whose grooves 12 and 13 are located in position to be engaged by the cam operating pins 14 and 15 carried by one of the side frames 3 for rocking the tumbler cam and thereby the gripper shaft, to open and close the grippers. The tumbler cam springs 16 and 17 are arranged as usual to hold the grippers in their open or closed position. Suitable stops 18 and 19 on the end of the rotary carrier are located in position to engage the tumbler cam 11 to limit the rocking movement of the rock shaft 5.

One or more, in the present instance two, auxiliary spring devices are shown for causing the grippers to exert the required added pressure on the sheet when the grippers are closed, each of which auxiliary pressure devices is constructed, arranged and operated as follows:

The rock shaft 5 has fast thereon within the gripper recess 6 an arm 20 which carries a stud or roller 21 located in position to be swung into and out of contact with a cam surface 22 of a spring pressed lever 23 as the grippers are closed and opened. As the grippers are closing, the stud or roller 21 will depress the lever 23 against the tension of its spring 24, thus causing the grippers to exert additional pressure on the sheet when the grippers are closed. It will be understood that the cam surface 22 of the lever 23 is so shaped that no pressure whatever is exerted on the grippers by the spring 24 when the grippers are open. A stop bar 25 serves to limit the outward movement of the cam lever 23.

It will also be understood that while two of these auxiliary gripper pressure devices are shown herein, one or more of said devices may be used to suit different requirements.

The arrangement hereinabove described permits the grippers to be operated with less noise and wear and yet have sufficient pressure when closed on the sheet to hold it firmly and evenly on the carrier. When the grippers are open they

will be entirely freed from this auxiliary pressure.

It is evident that various changes may be resorted to in the construction, form and arrangement of the several parts without departing from the spirit and scope of my invention, and hence I do not intend to be limited to the particular embodiment herein shown and described, but

What I claim is:

10. 1. A rotary sheet carrier, grippers carried thereby, a tumbler, a spring acting on the tumbler for holding the grippers open or closed, and means for separately exerting additional pressure on the grippers when closed.
15. 2. A rotary sheet carrier, grippers carried thereby, a spring pressed tumbler for holding the grippers open or closed, and means for separately exerting additional pressure on the grippers when closed, said grippers when open being freed from 20 said additional pressure.
20. 3. A rotary sheet carrier, grippers carried thereby, a tumbler, a spring acting on the tumbler at one end of the carrier for holding the grippers open or closed, and means located between the 25 ends of the carrier for separately exerting additional pressure on the grippers when closed.
25. 4. A rotary sheet carrier, grippers carried thereby, a spring pressed tumbler at one end of the carrier for holding the grippers open or closed, and means located between the ends of the carrier for separately exerting additional pressure on the grippers when open being freed from 30 said additional pressure.
30. 5. A rotary sheet carrier, grippers carried thereby, a tumbler, a spring acting on the tumbler at one end of the carrier for holding the grippers open or closed, and one or more devices located 35 between the ends of the carrier for separately exerting additional pressure on the grippers when 40 closed.
35. 6. A rotary sheet carrier, grippers carried thereby, a spring pressed tumbler at one end of the carrier for holding the grippers open or closed, and one or more devices located between the ends of 45 the carrier for separately exerting additional pressure on the grippers when closed, said grippers when open being freed from said additional pressure.
45. 7. A rotary sheet carrier, a rock shaft mounted 50 therein, grippers carried by the rock shaft, a tumbler on one end of the said shaft, a spring acting on the tumbler for holding the grippers open or closed, and means acting on said gripper shaft between its ends for separately exerting 55 additional pressure on the grippers when closed.
50. 8. A rotary sheet carrier, a rock shaft mounted therein, grippers carried by the rock shaft, a spring pressed tumbler acting on one end of the said shaft for holding the grippers open or closed, and means acting on said gripper shaft between 60 its ends for separately exerting additional pressure on the grippers when closed, said grippers when open being freed from said additional pressure.
65. 9. A rotary sheet carrier, a rock shaft mounted therein, grippers carried by the rock shaft, a tumbler on one end of said shaft, a spring acting

on the tumbler for holding the grippers open or closed, and one or more devices acting on the gripper shaft between its ends for separately exerting additional pressure on the grippers when closed.

10. A rotary sheet carrier, a rock shaft mounted 5 therein, grippers carried by the rock shaft, a spring pressed tumbler acting on one end of said shaft for holding the grippers open or closed, and one or more devices acting on the gripper shaft between its ends for separately exerting additional pressure on the grippers when closed, said grippers when open being freed from said additional pressure.

11. A rotary sheet carrier, a rock shaft mounted 10 therein, grippers carried by the rock shaft, a spring pressed tumbler acting on one end of the shaft to hold the grippers open or closed, a device acting on the gripper shaft between its ends for separately exerting additional pressure on the grippers when closed, said device comprising 15 a spring pressed lever having a cam surface, and an arm on the gripper shaft arranged to be swung into contact with said cam surface as the grippers are closed and out of contact with said cam surface when the grippers are open.

12. A rotary sheet carrier, a rock shaft mounted 20 therein, grippers carried by the rock shaft, a spring pressed tumbler acting on one end of the shaft to hold the grippers open or closed, a device acting on the gripper shaft between its ends 25 for separately exerting additional pressure on the grippers when closed, said grippers being freed of the additional pressure when open, said device comprising a spring pressed lever having a cam surface, and an arm on the gripper shaft arranged 30 to be swung into contact with said cam surface as the grippers are closed and out of contact with said cam surface when the grippers are open.

13. A rotary sheet carrier, a rock shaft mounted 35 therein, grippers carried by the rock shaft, a spring pressed tumbler acting on one end of the shaft to hold the grippers open or closed, a plurality of devices acting on the gripper shaft between its ends for separately exerting additional pressure on the grippers when closed, each of 40 said devices comprising a spring pressed lever having a cam surface, and an arm on the gripper shaft arranged to be swung into contact with said cam surface as the grippers are closed and out of contact with said cam surface when the grippers 45 are open.

14. A rotary sheet carrier, a rock shaft mounted 50 therein, grippers carried by the rock shaft, a spring pressed tumbler acting on one end of the shaft to hold the grippers open or closed, a plurality of 55 devices acting on the gripper shaft between its ends for separately exerting additional pressure on the grippers when closed, said grippers being freed of the additional pressure when open, each 60 of said devices comprising a spring pressed lever having a cam surface, and an arm on the gripper shaft arranged to be swung into contact with said cam surface as the grippers are closed and out of contact with said cam surface when the 65 grippers are open.

HOWARD M. BARBER.
